F. W. McDANIEL

SHEET REGISTERING PRONG

Filed Aug. 3, 1923

Inventor:

Floyd W. Mc Daniel

*By Wilson & Mc Daniel
H. H. G.*

UNITED STATES PATENT OFFICE.

FLOYD W. McDANIEL, OF APOLLO, PENNSYLVANIA.

SHEET-REGISTERING PRONG.

Application filed August 3, 1923. Serial No. 655,439.

To all whom it may concern:

Be it known that I, FLOYD W. McDANIEL, a citizen of the United States, residing at Apollo, in the county of Armstrong and State of Pennsylvania, have invented certain new and useful Improvements in Sheet-Registering Prongs, of which the following is a specification.

My invention relates to registering devices for printing presses, in which a prong receives one edge of a sheet fed from an automatic feeding device and is operated to position the sheet in registration with stops on the press platen. Heretofore, it has been customary to provide a number of sheet-registering forks to take care of sheets of different sizes within the capacity of the particular press and to provide additional forks for different grades of paper and cardboard; it being thus necessary to carry a complete line of sheet-registering forks and to select and set up the proper fork for each job.

The primary object of the present invention is to provide a single sheet-registering prong of the character described which will serve all purposes within the capacity of a given press. This result is obtained by reason of the novel construction of my sheet-registering prong, both as regards its adaptability for handling sheets of any thickness or texture and for accommodating any size sheet within the capacity of the press.

I have also aimed to provide a sheet registering prong embodying a novel sheet-gripping means, the tension of which may be varied to suit the particular work at hand.

Still another object is to provide a device of the character described which may be produced at a comparatively low cost and will serve in a practical and efficient manner the purposes intended.

Other objects and attendant advantages will be appreciated by those skilled in this art as the invention becomes better understood by reference to the following description when considered in connection with the accompanying drawings, in which—

Figure 1 is a top view of a sheet-registering prong, full size, embodying my invention;

Fig. 2 is a side view thereof;

Fig. 3 is a view of the flexible body strip; 55 and

Figs. 4 and 5 are enlarged sections taken substantially on the lines 4—4 and 5—5, respectively, of Fig. 1.

My improvement while adapted for sheet-registering devices of different kinds, is especially designed for use on a Miller feeder, this being an automatic sheet-feeding and registering mechanism well known to the printing trade. My sheet-registering prong may be used in place of the usual fork on such feeder, the body or shank of the prong being held by a set screw on a register element located on the lower platen edge of the press.

Referring more particularly to the drawing, it will be observed that I have provided a flexible spring steel body strip 7 of sufficient length to take care of the maximum length requirements of a prong of this kind.

One end of this strip is supported in and adjustable lengthwise with respect to the register element 9, shown briefly in the drawing. This register element is oscillated automatically in timed relation to the sheet-feeding mechanism for moving the registering prong to carry the sheet engaged thereby, as will be presently described, into the desired position on the press platen, as is well understood in this art. In practice, the strip 7 may be secured by means of the set screw 8 in any position to which it may be adjusted on the register element 9. The strip 7 has a sheet-engaging portion 11, preferably pointed as shown, 80 and adapted to engage a sheet from below.

The sheet is engaged from above by a steel ball 12 carried in a spring casing designated generally by 13, adjustably mounted on the strip 7. This casing in the present embodiment consists of a strip of spring steel having a flat end 14 adapted to bear against the top of body strip 7 and being turned back upon itself at 15, providing a portion 16 underlying and in spaced parallel 95 relation to the portion 14. These spaced portions 13 and 14 have round holes 17 therethrough in registration, each being of a diameter less than that of the ball. The ball may, therefore, be supported upon and 100 between the casing portions 14 and 16 in the

openings 17, free to rotate therein, and with a sheet-engaging portion 18 projecting from said casing. The semi-circular end 15 of the ball casing provides in conjunction with the tapered end 11, a converging mouth leading to the sheet-gripping surfaces, namely, the periphery of the ball and the opposed surface 11. This facilitates and insures accurate reception of the sheet.

10 Means is provided for adjustably holding the casing on the strip 7 with the sheet-engaging portion 18 of the ball positioned opposite said sheet-engaging portion 11 of the body strip. This means preferably 15 clamps the strips 7 and 14 together at any of different points throughout a greater portion of the length of the latter so that the tension of the sheet-engaging portions or members may be varied. In the present 20 instance, this means comprises a clamping yoke 19 and a clamping lever 21, these reference numerals being generally applied. The clamping yoke has a portion 22 underlying the strip 7 and upstanding arms 23 at 25 the sides thereof, and the clamping lever has a French journal on the arms 22, comprising trunnions 24 fitted in bearing holes 25 in the arms 23, and an eccentric portion 26 adapted to be brought into clamping engagement with the top of the casing strip 14 for clamping the latter to the strip 7 when the lever is moved to the position shown in full lines. Upon swinging the lever in a clockwise direction viewing Fig. 5, it will be 30 obvious that the eccentric portion 26 will be withdrawn from the member 14, thus releasing the clamped parts and permitting the yoke 23 to be shifted lengthwise upon and with respect to said clamped parts.

40 It will be manifest that by thus shifting the yoke and clamping it in the newly adjusted position, the pressure of the ball in its contact with a sheet will be in accordance with the tension of the part 14 of the ball casing, which part is in effect a flat spring, the length of which is varied by said adjustment. It will be noted that the effective length of this spring may be varied practically from its end 27 to approximately 45 the point 28. When making this adjustment, the ball casing may likewise be shifted on the strip 7 to position the sheet-engaging portion of the ball in the most effective relation to the sheet-engaging portion 11 of the understrip or tine, according to the size, thickness or texture of the sheet to be moved.

In use, especially on job presses where practically every printing job varies, the 60 registering prong must be properly adjusted and set for each job. By reason of the gripping action of the lower tine and upper ball and of the wide range of tension permitted by the present construction, this 65 prong is adapted to handle sheets of any

thickness or texture ranging from onion skin folio to six or eight ply cardboard. In regard to the different sizes of sheets and the location of the sheet on the platen, it will be manifest that by reason of the exceptional length of the strip 7, the prong may be extended or retracted as the case may be, and set for handling sheets from the largest to the smallest size. In the event that the prong is retracted to such a position that its end remote from the sheet-engaging end projects so that it would interfere with the press rollers and bed, this projecting end may be confined beneath a suitable wire loop or any such confining or retaining part secured to the gripper bar of the press. In such event, this end of the prong will be curved downwardly, and by reason of its flexibility will slide back and forth in its confined position during oscillation of the 75 prong in its registering and return strokes. In setting the prong, the ball should be positioned well up on the margin of the sheet, just so that the end of the prong clears the type on the printing stroke. On strictly 80 register and color work, accuracy is attained by so setting the prong that the ball does not leave the sheet on the end of the stroke. By the use of my invention, a stripper guide as is ordinarily used is not necessary. 90

It is believed that the foregoing conveys a clear understanding of the objects prefaced above, and it should be understood that while I have illustrated but a single working embodiment, changes may be made 100 in details of construction without departing from the spirit and scope of the invention as expressed in the appended claims.

I claim:

1. A sheet registering prong of the character described comprising a flexible body strip adapted at one end to engage a sheet from below, a ball adapted to engage the sheet from above, a ball casing, and means for adjustably securing the ball casing to the body strip for varying the sheet-contacting pressure of the ball. 105

2. A sheet registering prong of the character described comprising a body strip having a tine at one end shaped to engage a sheet from below, a ball adapted to engage the sheet from above, and means attached to said body strip yieldingly supporting the ball and permitting it to revolve freely in its operative position and being adjustable 115 upon and with respect to said body strip for varying the sheet-contacting pressure of the ball. 120

3. A sheet registering prong of the character described comprising a flexible body strip adapted at one end to engage a sheet from below, a sheet-engaging ball, a casing for the ball in the form of a flat spring adapted for yieldingly supporting the ball 125 in a position to engage the sheet from above, 130

and means for holding the ball casing on the body strip and for varying the spring tension.

4. A sheet registering prong of the character described comprising a flexible body strip adapted for attachment and lengthwise adjustment with respect to a register member and having a portion adapted to engage a sheet from below, a sheet-engaging ball, a casing supporting the ball so that it is free to rotate with a portion projecting, and means for securing said casing on said body strip with the projecting portion of the ball engaging the sheet from above and being adjustable for varying the sheet-contacting pressure of the ball.

5. A sheet registering prong of the character described comprising a flexible body strip adapted for attachment and lengthwise adjustment with respect to a register member and having a portion adapted to engage a sheet from below, a sheet-engaging ball, a casing supporting the ball so that it is free to rotate with a portion projecting, and means for securing said casing on said body strip with the projecting portion of the ball engaging the sheet from above, said means being adjustable for varying the pressure of the ball on the sheet.

6. A sheet registering prong of the character described comprising a flexible body strip adapted to be adjustably secured to a register part and shaped to engage a sheet from below, a sheet-engaging ball, a spring casing in which the ball is free to rotate and from which a sheet-engaging portion of the ball projects, and means for adjustably attaching said casing to the body strip.

7. A sheet registering prong of the character described, comprising a flexible body strip adapted for attachment to a register part and having a portion at one end

adapted for engaging a sheet from below, said strip being of sufficient length to permit adjustment of said registering part to 45 position said sheet-engaging portion to handle the maximum and minimum sheet-dimension and location requirements of a given press, and means on said strip for engaging the sheet from above, the end of the strip remote from its sheet-engaging end being by reason of its flexibility adapted when the strip is in a retracted position to be confined from interference with other parts of the press. 55

8. A sheet registering prong of the character described comprising a body strip adapted at one end to engage a sheet from below, a sheet-engaging ball, a casing for the ball in the form of a flat spring strip 60 bent upon itself at one end to provide substantially parallel spaced portions, said portions having registering ball-receiving openings therein in which the ball is supported with a portion projecting and adapted to 65 engage the sheet from above, and means for adjustably securing said ball casing to the body strip.

9. A sheet registering prong of the character described comprising a body strip 70 adapted at one end to engage a sheet from below, a sheet-engaging ball, a casing for the ball in the form of a flat spring strip bent upon itself at one end to provide substantially parallel spaced portions, said portions having registering ball-receiving openings therein in which the ball is supported with a portion projecting and adapted to 75 engage the sheet from above, a yoke slidable lengthwise on the body strip, and a clamping lever pivoted on the yoke and adapted for clamping the ball casing on the body strip. 80
